FRANK LUPPINO, OF WATKINS, NEW YORK.

SHOE AND METHOD OF MAKING SAME.

Application filed March 8, 1924. Serial No. 697,920.

This invention relates to improvements in methods of making shoes.

According to the present methods of making shoes, such as McKay nailed shoes, McKay sewed shoes, McKay nailed welt shoes, McKay sewed welt shoes, McKay turned welt shoes and the like, and welt and turned welt shoes of the Goodyear type, it has been necessary, when lasting such shoes, to provide an inner sole, which is placed on a last and to which parts of the shoe are permanently secured, such as the edges of the upper, the heel portion of the out sole, and the heel proper, as well as the welt strips in certain of the welt shoes. In the various McKay shoes, some of the parts are secured by nails which are clinched to the inner sole on the last, making it necessary to provide the completed shoe with an inner sole of some sort to cover said inner sole and the clinched nails, which nails extend not only around the edges of the front part of the shoe, but are also closely arranged at the heel portion due to the necessity of clinching the nails that secure the heel portion of the sole and also those that secure the heel proper to the inner sole. The remarks regarding the heel construction also apply to shoes of the Goodyear type.

Shoes constructed with the parts attached to the insole, as stated above, are very difficult and sometimes impossible to properly or expeditiously repair, and in the case of McKay nailed shoes, the removal of the worn sole weakens the shoe to an extent such that the new sole, which can only be nailed on, does not hold for any length of time. Further, the repairman finds it impossible to do repairing on the kinds of shoes mentioned without distorting the shape of, or breaking down the attached inner sole, with consequent discomfort to the wearer.

The particular objects of this invention are to provide a method of making shoes which have all the advantages of the kinds mentioned, such that the method may be practiced at a great saving in the cost of producing such shoes; also to provide a method whereby these shoes may be made complete on a single last without the use of expensive machines.

Another object of the present invention is to provide a shoe and a method of making the same, whereby a welt strip or the like may be used to take the place of the

usual inner sole for supporting the other parts of the shoe, said strip extending all around the shoe and providing a means for attaching the upper and outsole so as to leave the center of the bottom open or unobstructed above the outsole, whereby the upper and welt strip or strips may be stitched together from the inside.

Another object is to provide a method of making shoes in which an entirely separate and removable insole may be used to take the place of the usual final cemented insole, thereby making the shoe more easily accessible for repairs, and preventing, during repair work, the breaking or deformation of the insole; and whereby the wearer may use interchangeable insoles, or insoles having arch supporting or the like devices attached thereto and which may be removed with the insole when repairing the shoe, thereby also preventing the damage to such devices which usually occurs in repairing the shoe when these devices are built into the shoe beneath the usual permanent and non-removable insole.

Another object is to provide a method whereby a welt strip may be temporarily tacked to a last without an inner sole, and so that an upper, either turned or ordinary, may then be lasted to the strip and after lasting, the upper and strip may be removed as a unit and sewed together along their inner edges on the ordinary stitching machine through the aperture formed by said welt strip; also to provide a method whereby stitched shoes and stitched welt shoes of the kinds mentioned may be produced in which the entire outer edge of the outsole, including the heel portion, is secured to the shoe by stitching, and whereby an outer welt strip may be sewed to an upper on an ordinary stitching machine after the upper has been lasted to an inner welt strip through the aperture formed by said welt strip.

Still another object of the invention is to provide a method whereby, in welt shoes other than turned shoes, small pieces of scrap leather may be utilized in place of a continuous welt strip so that the scrap pieces perform the functions of the usual fixed inner sole for supporting the parts of the shoe at a great saving in cost.

Another object is to provide a method of making shoes whereby the shoes produced thereby may be easily and inexpensively

repaired, without the use of the various costly special stitching machines now required, and whereby in certain types of shoes a nailed shoe may be repaired as a sewed shoe, or vice versa.

Other objects of the invention are to improve shoes and methods of making the same in the other respects hereinafter specified and claimed.

10 In the accompanying drawings:

Fig. 1 is a plan view of a last of suitable construction for use in making shoes by the method embodied in this invention.

15 Fig. 2 is a fragmentary perspective view of a part of the last showing the method of temporarily securing a welt strip thereto.

Fig. 3 is a similar view showing a portion of a shoe upper lasted to the welt strip.

20 Fig. 4 is an enlarged fragmentary section of the last showing the welt strip tacked thereon.

Fig. 5 is a similar view showing the upper lasted to the welt strip as in Fig. 3.

25 Fig. 6 is a fragmentary perspective view of the welt strip and upper removed from the last after the upper has been lasted to the welt strip, and showing the two parts secured by stitches along their inner edges.

30 Fig. 7 is a fragmentary section showing the parts as in Fig. 6, replaced on the last and an out-sole secured thereon by nails to produce a shoe of the McKay nailed type.

35 Fig. 8 is a bottom plan view of a shoe of the McKay nailed type produced by the method embodied in this invention, with the sole and the upper partly broken away to show the welt strip and the inside working aperture.

40 Fig. 9 is a fragmentary enlarged section showing a shoe of the stitched welt type formed by the present method.

Fig. 10 is a similar view showing a shoe of the turned welt type.

45 Fig. 11 is a similar view showing a shoe of the Goodyear welt type formed by the present method.

50 Figs. 12 and 13 are transverse sections of a shoe of the McKay stitched type, and a shoe of the McKay stitched welt type respectively.

55 Fig. 14 is a longitudinal section of a shoe of the McKay stitched welt type, showing the method of stitching the heel portion of the outsole to the outer welt, and of securing the heel to the outsole.

60 According to the method of making shoes embodied in the present invention, a welt strip or the like is temporarily secured to a last, in place of the usual fixed inner sole which ordinarily supports the various parts 65 of the shoe, and the various parts of the shoe or some of the parts are secured to the welt strip. The welt strip thus forms a marginal band or member which takes the place of the usual inner sole, and provides an aperture or working opening, inside the

shoe, for permitting stitching to be done by any ordinary stitching machine. The welt strip also allows a separate, removable insole to be used, which covers the fixed welt strip or member and permits the easy and 70 practical repair of the shoe by providing access to the bottom parts from the inside for stitching new parts to the welt strip and upper.

75 The several operations by which the improved method is carried on are preferably performed on a single last, and it is desirable that the last should be so formed that both temporary tacking and permanent clinching operations may be performed on 80 it. A suitable last for this purpose is shown in Fig. 1, and comprises the usual wood front and rear body portions A and B, hinged together, and each having the usual flat metal bottom plate *a* and *b* respectively. These 85 plates are provided with the usual apertures C for permitting tacks to enter the wood to temporarily secure an outsole in place in the usual manner, and in addition, a series or row of apertures D are provided, 90 spaced from the edges and from each other, such that a welt strip or the like may be temporarily tacked to the last by its inner edge, preferably all around the last, while leaving a band E of imperforate metal 95 outwardly beyond the apertures D which is overlapped by the welt strip and which allows the clinching of nails, tacks or other metal securing devices in the subsequent 100 operations.

100 In the embodiment of the invention shown in the drawings, a shoe of the nailed McKay type is illustrated in the successive steps of production in Figs. 2-8. 10 designates a welt strip or the like which may be 105 of any suitable cross section, a variety of which are used in the art, and according to the kind of shoe required, a light or heavy welt strip is used. The welt strip 10 shown is provided adjacent one edge with a channel or stitch line 11. In applying the strip 10 to the last the channel 11 is disposed so as to lie substantially above the row of apertures D with the opposite edge of the strip extending to, or substantially to the 110 edge of the last. The strip 10 preferably extends around the last, and forms a continuous marginal member, and it is temporarily secured in place thereon as by lasting tacks 12 which pass through the strip 10 115 and the apertures D into the wood body portions A, B, see Figs. 2 and 4. An unlasted upper 13 of any usual or suitable form is now drawn over the last and the bottom or free edges 14 thereof are brought over on to the welt strip 10 and preferably secured thereto all around the last as by lasting nails 15 which pass through the edges 14 and through the strip adjacent the outer edge 120 thereof and are clinched by engaging the 125

marginal portions E of the last plates *a* and *b*. In this step the upper is of course first softened so that it may be shaped to the last, and after drying, the lasted upper 13 and 5 welt strip 10 may be removed together from the last, and owing to the fact that the welt strip is a marginal member only, the space between the opposite inner edges of the welt strip and edges 14 forms a working aperture 16 such that these inner edges are accessible and may now be stitched together by any suitable stitching machine. Such stitching is indicated at 17 Figs. 6 and 8.

In some cases, especially when an extra 15 heavy welt strip 10 is employed, it is unnecessary to use the lasting nails 15, in which case the upper end strip may be temporarily secured together by lasting tacks or the like, which will hold the parts together, as the strip will have sufficient thickness of material to hold the tacks in place. After the upper has dried on the last to its intended form, it may be removed with the strip and these parts secured together by 25 stitching as before, after which the tacks may be removed. This procedure is especially desirable when it is desired to substitute a second row of stitching in the place of the lasting nails 15.

30 The different steps of the invention, as thus far described are used in making all of the various types of shoes before mentioned, the succeeding steps however vary in accordance with the kind of shoe desired.

35 In the production of the McKay nailed shoe Figs. 2-8, the next step is to secure an outsole to the connected upper and welt strip. For this purpose, the upper and strip after being stitched together as described are

40 placed again on the last, or on any last having bottom plates or portions adapted to permit clinching operations to be performed. The outsole 20 is now placed on the last over the edges of the upper as usual, and is

45 preferably temporarily secured in position as by lasting tacks passing through it into the exposed wood of the last at the apertures C, or the outsole 20 may be temporarily secured by cement or otherwise. The

50 outsole is now secured to the connected edges of the lasted upper 13 and the welt strip 10, all the way around, by means of the usual nails, tacks or other metal securing means 21 adapted to be clinched over, by engaging the bottom plate, see Figs. 7, 8, and 12. It will be seen that by extending the

55 welt strip 10 all around the shoe, a support is provided to which the outsole 20 may be secured at the heel portion as well as at the front and sides, and this heel portion of the outsole, in turn provides a support for the heel proper which may be nailed securely thereto by clinching the nails, while nevertheless the heel is not attached to an insole

60 as in the usual constructions. If the shoe

is now removed from the last, a separate unattached insole 22 of any desired form may be inserted which will cover all of the exposed clinched ends of the nails or securing devices and will provide a smooth comfortable inner surface. An added advantage of the described construction resides in the fact that it permits the detachable insole 22 to be removed so that the inside of the shoe is exposed and is accessible to permit the 75 shoe to be repaired more quickly and in a more practical manner than it has heretofore been possible with present constructions. If, in cases where a relatively thick welt strip 80 is used, a cavity is formed between the inner edges of the strip such that the insole would be depressed therein in use and deformed, with consequent discomfort to the wearer, the cavity may, before the outsole is secured, be filled to the level of the upper 85 face of the strip with any suitable filler or waste leather. Thus a strong, sturdy shoe is produced which is of relatively light weight due to the fact that in place of a thick insole a marginal member only is 90 used, which also appreciably reduces the cost of production of shoes of this kind. When the welt strip used is of the well known thin tapering kind, no filling is needed as there will be no abrupt shoulder and no cavity sufficiently deep to cause the separate insole to be deformed.

A still further advantage obtains from the fact that with the present construction, detachable insoles having arch supporting devices or the like attached thereto may be used, and the devices can be adjusted or changed from time to time by removing the insole, and this arrangement allows said devices to be removed with the insole when the 100 shoes are to be repaired, thus precluding the possibility of damaging them by the pounding to which the shoes are subjected when on the last.

A shoe of the McKay stitched welt type, 110 formed in accordance with the method embodied in this invention is shown in Figs. 9, 13 and 14. In this construction the welt strip 10^a is tacked all around the last and the edge 14^a of the upper 13^a secured thereto 115 by stitches 17^a as before. To produce a McKay welt shoe, one or more outer welt strips must be arranged between the upper and the outsole in such a way that a flange or outwardly extended edge is produced to which the outsole may be secured by stitching. This outer welt strip is preferably arranged to extend all around the shoe so that the outsole may be secured thereto all around its edges. Fig. 9 shows such a welt strip, which may be secured to the connected upper 13^a and welt strip 10^a either by extending the strip around, in engagement with the edges of the upper and stitching it to the parts at the time the upper and inner welt 120

strip are stitched together, as by the stitches 26, or the welt strip 25 may be either temporarily tacked in place or permanently secured by a few lasting nails before the stitching takes place. After the welt strip 25 has been secured, an outsole 27, positioned on the last over the shoe parts as explained before, may be stitched, as at 28 to the outwardly extended edge 29 of the welt strip 10 or strips 25 by any suitable stitching machine. If desired the outsole 27 may be channelled as shown at 30 to conceal the stitches 28 and thereby effect a more finished appearance. If desired, in constructions employing an outer welt strip as just described the inner welt strip may be formed of a number of small pieces of waste leather, tacked on the last, end to end to form the continuous marginal member, so that the outer welt strip is relied on for maintaining the form of the upper and providing the necessary strength. Upon referring to Fig. 14 it will be seen that the stitches are carried all around the shoe and are adapted to securely attach the heel portion, as well as the front portion of the outsole 27 to the welt strip 25 and the strip 25 in turn is securely attached to the inner welt strip 10^b by the stitches 17^a. Thus the outsole 27 is adapted to take the place of the usual inner sole as a support for the heel proper 32, which is secured by the clinched nails 33 as in the McKay nailed type of shoe previously described. Thus the separate detached insole 22 may be removed at any time to permit access to the shoe bottom. The insole 22 in Fig. 13 is shown as having a rigid arch supporting device 34 secured to its under side, while in Fig. 14, a flexible device 35 of this sort is shown, of the sort adapted to be sprung or adjusted to hold a pad between it and the insole, the pad being interchangeable with pads of other form or thickness when desired. These devices are therefore removable with the insole and are not damaged when the shoe is repaired. A filling of any suitable sort may be used, as before, but this has been omitted in Fig. 14, to more clearly show the shoe construction. It is sometimes desirable in shoes of the sort just described to further secure the outsole by means of a few nails or securing devices adapted to pass through the parts to the upper face of the welt strip 10^a where they may be clinched against the bottom plates of the last. Such securing means are shown at 31 Fig. 9.

In making a shoe of the McKay turned welt type, see Fig. 10, the welt strip 10^b and upper 13^b are secured together as before, except that the upper is placed on the last wrong side out. The upper after being secured to the welt strip is then turned and lasted and the outsole 20^b is secured to the outwardly extending margin 35

of the welt strip 10^b by stitches or the like 36 all around the shoe. If desired a stiffening welt strip 37 may be secured inside the upper on the inner face of the turned in edges of the upper, by stitching through the welt strip 37, the edges 14^b of the upper and the welt strip 10^b.

In the production of shoes of the Goodyear welt type by the present method, the inner welt strip is adapted to take the place 75 of the usual permanently attached insole, thus making the shoe bottom more accessible for repairs, and providing a lighter shoe of equal strength and appearance at a reduced cost for material. A Goodyear welt construction is shown in Fig. 11, the inner welt strip 38 being channeled at 39 for attachment to the edge 40 of the upper, and the outer welt strip 41 is secured to both parts, all around the shoe, and provides an extended edge for the attachment of the outsole 42 also all around the shoe. If desired, an additional welt strip may be interposed between the outsole 42 and the welt strips 38 and 41. By this construction a working 85 aperture is provided inside the shoe to permit access to the shoe bottom, both in making the shoe and in the subsequent repairing, which is not possible with any of the Goodyear shoes now known. The aperture may 90 be filled as desired and this filling covered with a removable insole as before.

I claim as my invention:

1. A method of making shoes which consists in temporarily securing a welt strip 100 all around a last to form an endless marginal member and thereby forming an aperture inwardly of said strip, lasting an upper to the last and securing its edges to said marginal member, removing said upper and member from the last and stitching their edges together through said aperture, and securing an outsole to said upper and welt strip.

2. A method of making shoes which consists in temporarily securing a welt strip all around a last to form an endless marginal supporting member, and thereby forming an aperture within said member, lasting an upper to the last and securing its edges to said marginal supporting member, removing said upper and member from the last and stitching their edges together through said aperture, securing an outsole to said upper and welt strip by means of metallic securing devices which are passed through said outsole, upper and welt strip and are clinched over against the top face of said welt strip, whereby a shoe is formed in which access to said stitching and said securing devices may be had through said aperture.

3. A method of making shoes which consists in temporarily securing a welt strip all around a last to form an endless marginal member, and to produce an aperture inside

- 5 said strip, lasting an upper to the last and securing its edges to said marginal member, removing said upper and member from the last and stitching their edges together through said aperture, securing an outsole to said upper and welt strip, and inserting a separate detachable insole in said shoe to cover said welt strip and said aperture.
- 10 4. A method of making shoes which consists in temporarily securing a welt strip all around a last to form an endless marginal supporting member and thereby forming an aperture within said member, lasting an upper to the last and securing its edges to said marginal supporting member, removing said upper and member from the last and stitching them together through said aperture, securing an outsole to said upper and welt strip by means of metallic securing devices which are passed through said outsole, upper and welt strip and are clinched over against the top face of said welt strip, and securing a heel to the heel portion of said outsole so as to be supported thereby.
- 15 5. A method of making shoes which consists in temporarily securing a welt strip all around a last to form an endless marginal supporting member and thereby forming an aperture within said member, lasting an upper to the last and securing its edges to said marginal supporting member, removing said upper and member from the last and stitching their edges together through said aperture, attaching a second welt strip to said upper and said marginal member by stitching its inner edge to the inner edges thereof through said aperture, securing an outsole to the extended edge of said second welt strip and attaching a heel to the heel portion of said outsole so as to be supported thereby.
- 20 6. A method of making shoes which consists in temporarily securing a welt strip to a last having a flat metal bottom plate to form an endless marginal supporting member having an aperture within the same, lasting an upper to the last and securing its marginal portions to the welt strip, removing said last and strip and stitching them together through said aperture, attaching a second welt strip to said upper and said first welt strip so as to leave an outwardly extended edge, securing an outsole to said extended edge of said second welt strip and inserting a separate detachable insole in said shoe to cover said welt strip, whereby said outsole is accessible through said aperture by removing said detachable insole.
- 25 7. A method of making shoes which consists in temporarily securing a welt strip all around a last to form an endless marginal member and an aperture inside said strip, lasting an upper to the last and securing its edges to said marginal member, removing said upper and member from the last and stitching their edges together, attaching a second welt strip to said upper and said marginal member by stitching it to the inner edges thereof through said aperture, and securing an outsole to the extended edge of said second welt strip.
- 30 8. A method of making shoes which consists in temporarily securing a welt strip all around a last to form an endless marginal supporting member and thereby forming an aperture within said member, lasting an upper to the last and securing its edges to said marginal supporting member, removing said upper and member from the last and stitching their edges together through said aperture, attaching a second welt strip to said upper and said marginal member by stitching its inner edge to the inner edges thereof through said aperture, securing an outsole to the extended edge of said second welt strip and attaching a heel to the heel portion of said outsole so as to be supported thereby.
- 35 9. A method of making shoes which consists in temporarily securing a welt strip to a last having a flat metal bottom plate to form an endless marginal supporting member having an aperture within the same, lasting an upper to the last and securing its marginal portions to the welt strip, removing said last and strip and stitching them together through said aperture, attaching a second welt strip to said upper and said first welt strip so as to leave an outwardly extended edge, securing an outsole to said extended edge of said second welt strip and inserting a separate detachable insole in said shoe to cover said welt strip, whereby said outsole is accessible through said aperture by removing said detachable insole.

FRANK LUPPINO.
